CLAIM

The ornamental design for a cooking pot, as shown and described.

DESCRIPTION

FIG. 1 is a perspective view of a cooking pot according to my new design;

FIG. 2 is a first side view of the cooking pot shown in FIG. 1 the second side view being a mirror image thereof;

FIG. 3 is a front view of the cooking pot shown in FIG. 1, the rear view being a mirror image thereof;

FIG. 4 is a top view of the cooking pot shown in FIG. 1; and,

FIG. 5 is a bottom view of the cooking pot shown in FIG. 1.

The dot-dash lines in the drawings illustrate the bounds of the claim and form no part thereof.

1 Claim, 5 Drawing Sheets(56)
